(57) **CLAIM**

The ornamental design for an adjustable stand, as shown and described.

DESCRIPTION

FIG. 1 is a front perspective view of an adjustable stand of the present disclosure;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view showing a portion of FIG. 1;

FIG. 10 is an enlarged view showing a portion of FIG. 1;

FIG. 11 is an enlarged view showing a portion of FIG. 3;

FIG. 12 is an enlarged view showing a portion of FIG. 3;

FIG. 13 is an enlarged view showing a portion of FIG. 4;

FIG. 14 is an enlarged view showing a portion of FIG. 4;

FIG. 15 is an enlarged view showing a portion of FIG. 5;

FIG. 16 is an enlarged view showing a portion of FIG. 6;

FIG. 17 is an enlarged view showing a portion of FIG. 7;

FIG. 18 is an enlarged view showing a portion of FIG. 7;

FIG. 19 is an enlarged view showing a portion of FIG. 8;

and,

FIG. 20 is an enlarged view showing a portion of FIG. 8.

The shading is not a feature of the design but is utilized to illustrate the surface contours of the adjustable stand design in the drawings. The broken lines in the drawings show portions of the adjustable stand that form no part of the claimed design.

1 Claim, 20 Drawing Sheets
